UNITED STATES PATENT OFFICE.

IRVING R. BAILEY, OF AKRON, OHIO, ASSIGNOR TO THE GOODYEAR TIRE AND RUBBER COMPANY, OF AKRON, OHIO, A CORPORATION OF OHIO.

DESIGN FOR A RUBBER HEEL.

53,060.

Specification for Design.

Patented Mar. 11, 1919.

Application filed November 2, 1914. Serial No. 869,986. Term of patent 14 years.

To all whom it may concern:

Be it known that I, IRVING R. BAILEY, a citizen of the United States, residing at #76 Rose avenue, in the city of Akron, county of Summit, and State of Ohio, have invented new, original, and ornamental Design for Rubber Heels, of which the following is a specification, reference being had to the accompanying drawing, forming a part thereof.

Figure 1 of the drawing is a perspective

view of a rubber heel showing my new design, and Fig. 2 is a transverse sectional view taken upon line II—II of Fig. 1.

I claim:

The ornamental design for a rubber heel, as shown.

IRVING R. BAILEY.
